CLAIM

The ornamental design for a motorcycle fairing rack, as shown and described.

DESCRIPTION

FIG. 1 is a rear view of a first embodiment of the motorcycle fairing rack showing my new design;

FIG. 2 is a front view of the embodiment of FIG. 1;

FIG. 3 is a rear view of a second embodiment thereof;

FIG. 4 is a front view of the embodiment of FIG. 3 thereof;

FIG. 5 is a rear view of the embodiment of FIG. 1 as mounted on a motorcycle, the motorcycle environment being shown in phantom; and,

FIG. 6 is a rear view of the embodiment of FIG. 3 similar to the position of the fairing of FIG. 5, but without the motorcycle environment being shown at all.
